CAM ACTUATED WORK CLAMP MEANS MOVABLE CONTINUOUSLY IN A ROTARY PATH

Horace E. Farmer, Howell, Mich.

Application August 3, 1955, Serial No. 526,222

3 Claims. (Cl. 10—107)

This invention relates generally to automatic machine tool machinery and particularly to thread cutting machines.

It is the principle object of my invention to provide an improved machine for threading the shanks of workpieces by an arrangement such that this operation may be performed efficiently on a high production basis.

Another object of the invention resides in having a rotatable workpiece carrier or trunnion which rotates continuously, as opposed to the station to station movement formerly employed, whereby a continuous flow of threaded parts is produced by the machine.

Another object of the invention is to utilize the continuous rotating movement of the workpiece carrying trunnion to actuate automatically a workpiece fixture clamp; to rotate thread cutting dies; and to advance and retract the dies with respect to the workpieces.

Other objects of the invention will become apparent from the following description, taken with the accompanying drawings in which:

Fig. 1 is a side elevational view having parts broken away and in section of my thread cutting machine;

Fig. 2 is a fragmentary enlarged section taken along line 2—2 of Fig. 1;

Fig. 3 is a front view partly broken away and in section, taken along line 3—3 of Fig. 1;

Fig. 4 is a fragmentary plan view of one of the thread cutting dies and associated parts;

Fig. 5 is a vertical section, taken along line 5—5 of Fig. 1;

Fig. 6 is an enlarged view in section, taken along line 6—6 of Fig. 3;

Fig. 7 is a side view partly broken away and in section of a holding fixture of the machine;

Fig. 8 is a front view partly broken away of the fixture;

Fig. 9 is an enlarged, fragmentary view of the fixture;

Fig. 10 is an enlarged, vertical fragmentary section showing details of a valve, and

Fig. 11 is a cross sectional view of the valve, taken along lines 11—11 of Figs. 1 and 10.

Referring to the drawings by characters of reference, my thread cutting machine comprises, in general, a support or base 20 having front and rear uprights or standards 22 and 24 respectively which support a horizontal shaft 26 therebetween. The shaft 26 is held against rotation and journaled on said shaft to rotate thereabout is a trunnion 28. A key 30 (see Fig. 10) or other suitable means may be employed to hold shaft 26 to the standard 22 to prevent rotation of the shaft.

The trunnion 28 has a rear hub 32 which is preferably journaled by roller bearing on shaft 26, and surrounding the shaft 26 and fixed to the end of the hub 32 is a worm wheel 34. A worm gear 36 drives the worm wheel 34 and in turn may be driven by an electric motor and suitable speed reduction mechanism (not shown). Between the rear standard 24 and the trunnion 28, a housing 38 encloses the worm wheel 34 and gear 36, and is bolted or

otherwise secured to base 20, as shown more clearly in Fig. 5.

Intermediate its front and rear ends, the trunnion 28 has a drum 40 of larger diameter than the trunnion proper which drum carries a number of radially spaced tool holders 42 adjacent the outer periphery thereof. Each of the tool holders 42 includes a movable member or carrier 44 which may be in the form of a tube or sleeve, as shown. These carriers 44 have their longitudinal axes parallel to the axis of rotation of the trunnion 28 and extend through the front of the drum 40. Bushings 46 in the drum 40 receive the carriers 44, the carriers being arranged to slide axially on the bushings or longitudinally of the drum axis during the thread cutting operation to effect the lead of the thread.

Carried by each of the carriers 44 is a rotatable shaft 48 which is concentric with the carrier and is journaled for rotation therein on suitable bearings 50. At the front of the machine, the shafts 48 project from the carriers 44 and affixed to the projected end of each shaft 48 is a suitable threading die 52. The other or rear ends of shafts 48 project from the drum 40 into a gear casing 54 formed by the rear drum wall and a housing 56 secured thereto. Within gear casing 54, the die carrying shafts 48 have reduced end portions 58 and fixed to each, such as by splines, is a gear 60. Adjacent to each of the shafts 48 is a stub shaft 62 which is carried by the drum and has one end fixed to the drum rear wall such that the shafts 48 and stub shafts 62 are parallel. Within the gear casing 54, a rotatable sleeve gear 66 is journaled for rotation on each of the stub shafts 62 and keyed, as at 68, to the sleeve gear 66 is a larger gear 70 which meshes with gear 60 to drive the shafts 48. Fixed to the trunnion 28 adjacent to the rear end of the drum 40 is a large driving gear 72 which meshes with the sleeve gears 66. Thus, it will be seen that rotation of drum 40 effects driving of the several gears including drive gear 72, sleeve gear 66, gear 70 and gear 60 thereby to drive or rotate all of the die carrying shafts 48.

Within the drum 40, a cam member 74 in the form of a ring or sleeve is fixed to the outer periphery of a ring-like holder 76 which has a hub 78 that fits over and is keyed as at 79, to shaft 26 to hold the cam member against rotation. In the outer surface of the cam member 74 and extended continuously around the cylindrical surfaces is a cam groove 80 to advance the die carriers 44 in accordance with the lead of the thread to be cut and to retract the carriers after the thread cutting operation. Fixed to the outer periphery of each of the carriers 44 is a cam follower 82 engaging in the cam groove 80. Split clamps 84 may be used to clamp the followers 82 to the carriers 44, the followers 82 being rotatable on shafts 86 which screwthread into the clamps and are held against movement by set screws 88 (see Fig. 6). It will now be seen that when the trunnion 28 is rotating it rotates the die carrying shafts 48 through the individual gear trains provided therefor and also moves the carriers 44 axially by means of the cam groove 80 and followers 82. The cam groove 80 is designed such that it moves each of the carriers 44 axially as the shaft 48 carried thereby is rotating the die, thus imparting a helix movement to cut the thread, the lead of the thread being determined by the design of cam 80 and the speed of rotation of shafts 48.

Carried by the trunnion 28 is a number of radially spaced workpiece holding fixtures 90 which are respectively aligned with the thread cutting dies 52. In the present instance, the workpieces are pinion drive shafts 92 having an outer shank end 94 on which the machine cuts the desired thread as the thread cutting dies and fixtures rotate during one revolution with the trunnion. The fixtures 90 are alike and are mounted on the trunnion at the

front of the machine for convenient access by an attendant whose job is simply to remove the finished workpieces and replace them with unthreaded workpieces as the trunnion rotates. The fixtures each include a holder 96 which preferably is provided with spaced aligned wear bushings 98 to receive the workpiece 92.

A locking member or clamp 100 provided for each fixture is automatically actuated by rotation of the trunnion 28 to hold each shaft 92 tightly to its holder 96 during the thread cutting operation. As shown, the clamp 100 in rod form is arranged such that when moved upwardly the upper end thereof makes wedging contact with the outer end of the workpiece 92 urging the workpiece inwardly and tightly against the bushings 98. The clamp 100 is formed with a gear rack 102 extending therealong which meshes with a gear 104 on one end of a shaft 106 such that rotation of the shaft 106 in one direction moves the clamp upwardly to clamp the workpiece 92 to its holder, and rotation of the shaft 106 in the opposite direction withdraws the clamp 100 to release the workpiece 92. On the other end of shaft 106 is a gear 108 which meshes with a gear rack 110 that is formed on a clamp operator or cam follower rod 112. This rod 112 is reciprocated by a cam 114 which surrounds and is fixed to shaft 26 such as by means of a key 116, Fig. 1. The cam 114 is designed such that as the thread cutting operation is completed on each of the workpieces 92, the cam follower 112 moves to rotate shaft 106 in a direction to retract the clamp 100 which remains retracted sufficiently long enough to allow the machine attendant to remove the finished piece and place another workpiece in the fixture holder 96.

In each of the fixture holders 96, the shaft 106 is journaled therein for rotation about a horizontal axis. As is shown more clearly in Fig. 7, the follower 112 has a tubular upper portion to receive a spring 116 which at its upper end has an adjustable seat 118 for adjustment of the spring compression. Spring 116 urges the follower 112 inwardly against the cam 114, and the inner ends of the followers are preferably provided each with a roller 120 to reduce friction with the cam. With particular reference to Fig. 9, the fixture clamp 100 is preferably provided in its outer surface with a guide slot 122 which extends lengthwise of the clamp to receive a guide pin 124 so as to prevent turning of the clamp. The guide pin 124 may be an unthreaded shank portion of a screw 126 which may be screwthreaded into the side of the fixture holder or body 96.

During the thread cutting operation on each of the workpieces, it is desirable that a coolant be sprayed thereon and it is also desirable that coolant flow be interrupted during the interval when the machine attendant is removing a finished workpiece and replacing it with another to be threaded. In order to accomplish the above automatically, I provide a valve 130 to control flow of the coolant to the workpieces and dies in accordance with rotation of the trunnion 28. The valve 130 includes a casing 132 which surrounds shaft 26 and is held thereto against rotation by a set screw 134. Rotatable with the trunnion 28 and fitting closely over the cylindrical casing 132 is a valve member 136 which may be connected to the trunnion 28 by a drive pin 138. The rotatable valve member 136 is provided with radially spaced bores or passages 138 connected by conduits 140 which conduct coolant to the workpieces and dies. The valve casing is provided with an inlet 142 which may be connected to a suitable source of coolant which is usually pumped from the source to the part or parts to be cooled. The inlet 142 discharges into a chamber 144 in the casing which chamber is annular or encircles the shaft communicating with the individual outlet passages 133. On the rotatable valve member 132 is an arcuate valve portion 146 which extends into the annular chamber 144 and closes the passages 138 to flow

therethrough for the interval during which the attendant removes a finished workpiece and places another in the fixture. The valve is designed such that coolant is allowed to flow to all workpieces in the process of having the thread cut thereon.

The thread cutting dies 52 have not been shown or described in detail as such dies are well known in the art. The present dies 52 are of the type which may be opened to receive the shank end 94, of the workpiece 92 and then closed to perform the threading operation. To open and close the dies 52 each is provided with a pair of forks 150 which are secured to and rotate with the trunnion 28. When the die carrier 44 is moved outwardly by cam 80, the die will be engaged and opened by one of the forks 150 to receive the workpiece shank 94 and continued movement of the carrier 44 will engage the other fork 150 and close the die. It will be understood that during this time, the die is rotating since the trunnion 28 continuously rotates during production. When the threading operation is complete the die opens and is retracted on its carrier 44 by the cam 80.

Operation

In operation, the motor driven shaft, driving through the worm 36 and worm wheel 34 rotates the trunnion 28 on which the large gear 72 drives or rotates the shafts 48 of all of the die carriers 44 simultaneously. Also, as the trunnion 28 rotates, the followers 112 carried by the trunnion drum 40 move the die carriers 44 axially or rectilinearly for the purpose of establishing the lead of the thread being cut. On completion of the thread cutting operation on one of the workpieces, the die 52 is opened by one of the forks 150 and then the fixture clamp 100 is retracted permitting the machine attendant to remove the workpiece 92 and replace it with another to be threaded. The fixture clamp 100 is actuated by the trunnion operated cam 114 and follower 120 to lock the workpiece in its fixture all of which takes place as the trunnion rotates. The trunnion operated cam 80 then advances the die 52 which opens to receive the workpiece shank 94 and closes during which time the die is being rotated by the trunnion through the gear trains driven thereby. Also, the trunnion operated cam 80 advances the die at a rate corresponding to the desired lead of the thread being cut and when the thread is completed one of the forks 150 opens the die to discontinue the cutting operation, the die continuing to rotate, but being retracted to a position to start the cutting operation on the next workpiece. From the above, it should be understood that the workpieces 94 are in different positions with respect to completeness of the operation. For example, as the thread cutting operation on one workpiece is completed and the workpiece replaced, the successive workpieces in the fixtures are in different stages of completion, so that there is a continuous flow of threaded workpieces produced from the machine. As previously mentioned the coolant flow control rotary valve 130 is driven by the trunnion 28 and cuts off flow of coolant to the thread and die of each unit as it reaches the finished position whereby the attendant may remove and replace the workpieces 94 while the coolant flow thereto is turned off.

From the above description, it will now be understood that I have provided a new and improved thread cutting machine of a character such that a plurality of workpieces can be threaded at the same time, but in such a way that they are in different stages of completion with the result there is a continuous supply of threaded workpieces coming from the machine. The success of this high production operation lies in having the plurality of radially spaced fixtures and a plurality of radially spaced corresponding threading dies mounted on a rotating trunnion or drum and operated by the rotation whereby a completed workpiece is produced for each rotation of the trunnion. That is, whereas in the present machine

six dies are used, the machine will produce a thread on a workpiece for each 60 degrees of travel of the trunnion.

While I have shown and described my invention in detail, it is to be understood that many modifications and variations may be made without departing from the spirit and scope of the invention.

I claim:

1. In a tool operating machine, a support, a fixed cam on said support, a trunnion mounted on said support and rotatable about said fixed cam, a workpiece holder carried by said trunnion outwardly thereof, a reciprocal clamp bar carried by said trunnion and slidably guided thereby, said clamp bar movable lengthwise thereof relative to said trunnion between workpiece clamping and releasing positions, a radially reciprocal cam follower carried by said trunnion and reciprocal by said cam, said follower spaced from said clamp bar axially of said trunnion, and gear and rack means operatively connecting said cam follower and said clamp bar.

2. In a tool operating machine, a support, a fixed cam on said support, a trunnion mounted on said support and rotatable about said fixed cam, a workpiece holder carried by said trunnion outwardly thereof, a reciprocal clamp bar carried by said trunnion and slidably guided thereby, said clamp bar movable lengthwise thereof relative to said trunnion between workpiece clamping and releasing positions, a radially reciprocal cam follower carried by said trunnion and reciprocal by said cam, said follower spaced from said clamp bar axially of said trunnion, a shaft rotatably mounted on said trunnion and

20

25

30

extending between said cam follower and said clamp bar, and means on said cam follower and shaft and on said clamp bar and shaft operatively connecting said cam follower and clamp bar together.

5. 3. In a tool operating machine, a support, a fixed cam on said support, a rotatable trunnion on said support, a workpiece holder carried by said trunnion, a clamp bar carried by and reciprocal relative to said trunnion, said clamp bar having its reciprocal axis inclined with respect to the axis of rotation of said trunnion and cooperable with said workpiece holder to clamp and unclamp a workpiece, a reciprocal cam follower carried by said trunnion and cooperable with said cam, said cam follower spaced from said clamp bar longitudinally of the axis of said trunnion, a gear rack on said clamp bar, a gear rack on said cam follower, and gear means connecting said racks rotatably mounted on said trunnion.
